K. F. NYSTROM.
TRUCK CONSTRUCTION.
APPLICATION FILED JULY 12, 1920.

1,404,886.

Patented Jan. 31, 1922.

By Arthur Langford Atty. S.

UNITED STATES PATENT OFFICE.

KARL F. NYSTROM, OF MONTREAL, QUEBEC, CANADA.

TRUCK CONSTRUCTION.

1,404,886.

Specification of Letters Patent. Patented Jan. 31, 1922.

Application filed July 12, 1920. Serial No. 395,686.

To all whom it may concern:

Be it known that I, KARL F. NYSTROM, a citizen of the Dominion of Canada, and resident of the city of Montreal, in the Province of Quebec and Dominion of Canada, have invented certain new and useful Improvements in Truck Construction, of which the following is a full, clear, and exact description

10 This invention relates to improvements in car truck construction and more particularly to improvements in the pedestals forming part of the truck

15 The object of the invention is to provide a truck in which the equalizers will be supported in case of breakage and held against dropping onto the track

A further object is to provide an improved bottom connection for the pedestals.

20 The equalizers in use, in passenger car or pedestal type trucks, are so formed that their point of greatest weakness is at the upper bend where they overlie the journal boxes and it frequently happens that they break at 25 this point, with the result that the bar drops. While the equalizer bars are positioned some distance outside the rails and should theoretically fall clear of the rails, it nevertheless sometimes happens that a broken equalizer

30 will fall across a rail and cause derailment of one or more trucks. It will thus be seen that the construction ordinarily used is a constant menace. There is nothing in the construction of any part of the truck which 35 will support the equalizer and hold the same against dropping out of the truck in case of breakage. Another source of accident is the dropping of pedestal tie-bars. Derailment from this source is not probable and the 40 truck is still capable of running but the jaws of the pedestal are subjected to undesirable stress which frequently results in breakage of a pedestal.

According to the present invention, the 45 truck pedestals are provided with means for gripping the broken end of an equalizer and holding the same, so that it will not drop out of the truck. At the same time the pedestals are so formed that the tie-bars cannot 50 drop out of the pedestals.

In the drawings which illustrate the invention:—

Fig. 1 is a side elevation of a truck pedestal partly in section.

55 Fig. 2 is a side elevation of the pedestal.

Fig. 3 is a section on the line 3—3, Figure 1.

Fig. 4 is a fragmentary section illustrating a modification.

Referring more particularly to the drawings, 11 designates the outer plate and 12 the inner plate of a truck pedestal, each formed in substantially inverted U-shape and connected by webs 13 to form the jaws 14 of the pedestal. The webs 13 have apertures 15 for the passage of equalizers 16. This is the ordinary construction and varies slightly in detail according to the particular type of truck. The weak point of the equalizer is at the upper bend, as has been previously stated, and fracture when it occurs is usually at about the line 17. The obvious result is, that the equalizer loses its support on the journal box and the end draws out from between the inner and outer plates and falls out of the truck.

According to this invention, a supplementary web 18 is provided between the outer and inner plates and is disposed substantially in parallelism with the lower edge 80 surface of the equalizer, i. e. in an inclined plane. This web forms a table or support below the equalizer of such width that the equalizer cannot slip off the edge.

The equalizer is much narrower at the end 85 than toward the center in order that it may be entered into the pedestal without providing an unduly deep pedestal. This reduction of width is, to a certain extent, compensated for by simultaneously increasing the thickness 90 of the bar as is well known and as is illustrated in Figure 2. Advantage is taken of this increase in thickness. The adjacent surfaces of the outer and inner plates are provided with ribs 19 which approach each other toward the table 18 and form a tapering notch through which the equalizer passes.

Normally, the equalizer is supported by the journal box some distance above the table 18 and sufficiently spaced from the 100 ribs 19 to permit the necessary movement of the equalizer. In the event of fracture at or about the line 17 the equalizer, being deprived of the support of the journal box, drops toward the table and thereby enters 105 the narrow space between the lower ends of the ribs 19. At the same time the equalizer tends to slide down, and this sliding movement brings portions of increased thickness between the ribs 19. After very slight move- 110

ment the end of the equalizer is wedged tightly between the ribs 19 and is supported either directly upon the table 18 or indirectly through the ribs 19. Obviously, this wedging action of the equalizer tends to force the outer and inner pedestal plates apart. The table 18 connects the plates close to the application of the separating force and holds the same rigid, so that they are not damaged by the wedging action of the broken equalizer.

It is customary, in truck pedestal construction, to connect the lower ends of the pedestal jaws by a tie-bar for the purpose of making the jaws mutually supporting and also to retain the journal boxes. These tie-bars are ordinarily mere metal straps passing under the ends of the jaws and connected thereto by bolts and nuts. It frequently happens that one or more of the nuts holding a tie-bar becomes loosened by vibration and drops, thus allowing the tie-bar to drop away from the pedestal jaw and depriving the jaw of support.

According to this invention the pedestal jaws are extended downwardly a short distance and provided with horizontally disposed apertures or slots 20, through which the tie-bars 21 extend. In the drawings there is illustrated a short tie-bar serving only a single pedestal. It is obvious, however, that a longer bar connecting the two or more pedestals may be used or that short bars as shown may be connected together in any suitable manner if it is desired to brace the whole truck. Such an arrangement is immaterial to the present invention. Whatever the form of the tie-bar, it is preferably provided with a downturned lug or projection 22 designed to engage one jaw of the pedestal. The opposite end is apertured for the passage of the usual bolt or pin 23. It will be readily seen that, according to this invention, the tie-bar is supported by the pedestal itself and that the pin or bolt 23 serves merely to hold the tie-bar against longitudinal movement. The bolt 23 may be provided with a nut or cotter pin but this is merely for the purpose of holding the tie-bar against vibration, as the bolt will be held in place by the force of gravity and will therefore maintain operative engagement with the tie-bar. The projection 22 of the tie-bar may replace one of the bolts 23 ordinarily used in each pedestal but this arrangement may obviously be modified by the form of tie-bar used. The arrangement shown holds the pedestal jaws against separating but does not transmit force in both directions between the jaws. It may therefore be preferred to use a bolt or pin 23 in each jaw. Either of the pin arrangements will serve to transmit the strain or drag of a broken equalizer from one pedestal jaw to the other, so that both

jaws co-operate to an extent in supporting a broken equalizer. The absolute reliability of the connection between the pedestal jaws gives the assurance that this mutual support will be always available in the event of 70 equalizer failure.

Obviously the pedestal should be exactly the same on both sides, so that it may be used in any position on a truck. To this end each jaw is provided with a table 18, 75 the rib 19 and bolt holes 24. An aperture 25 may be provided in the table 18 for the introduction of the pin or bolt 23 but if alternate disposition of the table in a different design of pedestal admits of the omission of 80 this opening 25, it is obviously preferred to have the solid table without opening, as shown in Figure 4. In this figure an opening 26 is provided in the web 13 giving access to the bolt hole 24.

Having thus described my invention, what I claim is;—

1. In truck construction, a pedestal including outer and inner plates and a web connected between the plates in position to support the end of a broken equalizer.

2. In truck construction, a pedestal including spaced side portions and an inclined web connected between said side portions in position to support the end of a broken 95 equalizer.

3. In truck construction, a pedestal including outer and inner plates and converging ribs on the adjacent surfaces of said plates forming jaws adapted to grip the 100 dropped end of a broken equalizer.

4. In truck construction, a pedestal including outer and inner plates and ribs on the adjacent surfaces of said plates positioned to be normally out of engagement 105 with an operative equalizer but to receive and wedge between them the fallen end of a broken equalizer.

5. In combination with a device according to claim 3, a supplementary rib connecting 110 the outer and inner pedestal plates and rigidly supporting the same adjacent said ribs.

6. In car truck construction, a pedestal, and means therein to grip the fallen end of a broken equalizer.

7. In car truck construction, a pedestal, means therein to support the fallen end of a broken equalizer, and means to grip the equalizer and hold the same against sliding out of engagement with said support.

8. In truck construction, the combination with a pedestal and an equalizer increasing in thickness toward its ends, of jaws in the pedestal disposed below the normal equalizer position and embracing said equalizer 125 at a point where the thickness thereof is less than the maximum, said jaws being spaced apart a distance less than the maximum thickness of the equalizer.

9. In combination with a device according 130

to claim 8, a web in the pedestal supporting said ribs against separation by wedging action of the equalizer.

10. In combination with a device according to claim 8, a web in the pedestal positioned to form a direct support for a fallen equalizer.

11. In track construction, a pedestal, and means in each jaw thereof to grip and support a broken equalizer, and a connection between the pedestal jaws arranged to distribute between the pedestal jaws the abnormal stresses incident to equalizer breakage.

15 12. In truck construction, a pedestal apertured adjacent the lower ends of its jaws and provided with a bore intersecting one of

said apertures, a pedestal supported tie bar passing through the apertures having one end provided with a stop projection engaging the pedestal and thereby holding the bar against longitudinal movement in one direction, and a removable member supported by the pedestal and passing through the bore of the pedestal and through the tie bar to hold the latter against longitudinal movement in the opposite direction, said member being entirely relieved of the weight of the bar by the walls of the apertures through which the bar extends.

In witness whereof, I have hereunto set my hand.

KARL F. NYSTROM.
